Inventor
F. McManus

United States Patent Office.

F. McMANUS, OF ELLENBURG CENTRE, NEW YORK.

Letters Patent No. 88,055, dated March 23, 1869.

RAILROAD-CAR HEATER

The Schedule referred to in these Letters Patent and making part of the same.

To all whom it may concern:

Be it known that I, F. McMANUS, of Ellenburg Centre, in the county of Clinton, and State of New York, have invented a new and useful Improvement in the Method of Heating Railroad Passenger-Cars; and I do hereby declare that the following is a full, exact, and clear description of the same, which will enable others skilled in the art of making and using the same, reference being had to the accompanying drawings, forming part of this specification, and in which—

Figure 1 represents a side elevation of the interior and bottom of a passenger-car;

Figure 2, a floor view of the same, showing both sides of the seats, and the aisle in the middle;

Figure 3 represents the chamber for holding the heater; and

Figure 4 represents the smoke-flue leading from the pipe of the heater through each side of the car.

The object of this invention is to provide a suitable and effective means for thoroughly disseminating heat in cars, and, in so doing, preventing or obviating the incumbrances attendant thereupon in the construction of the ordinary car-heater; and

The nature of my invention consists in the combination and general arrangement of such devices as will be hereinafter particularly described.

In the accompanying drawings is represented a passenger-car.

In the space between the upper and lower part of its floor, are situated the chambers A A, directly beneath the seats in the car, and made of suitable dimensions.

Secured to the under side of the floor, at its centre, is the box, or chamber, B, which is provided at one end with the trap-door F, as seen in fig. 3.

In this chamber is placed the heater H, which is securely fastened therein in any suitable way.

E represents the smoke-flue, or chamber, which is

situated between the heating-chambers A A, directly over the pipe of the stove, or heater with which it is connected.

This chamber E is provided with a partition, I, which extends from the point where it connects with the heater to the point where said flue is provided with branch-pipes, for the purpose of conducting the smoke in different directions, as seen by the red arrows in fig. 4.

By the employment of the partition I in the smoke-flue E, the draught is caused to flow in equal proportions in the two directions, toward the front and rear of the car.

O represents grates, or registers, placed in front of the seats, or under the feet of their occupants, to admit the heat into the car, the grates being set in a portion, G, of the car-floor, which is hinged to the main portion of the floor, so as to allow of its being taken or raised up, to remove any sediment or dirt that may have fallen through the grate.

D represents the main grate, or register, which is placed directly over the car-heater in box B.

I am aware that a chamber containing a heater, with side-chambers, registers, and smoke-flues connected therewith, have been before employed; but I am not aware that the said parts have been heretofore combined and arranged, as in my invention; nor am I aware that a partition has heretofore been used in the smoke-flue for the purposes set forth in my invention.

What I claim, and desire to secure by Letters Patent, is—

The chamber B, side-chambers A A, registers C C, and smoke-flue E, provided with partition I, all being constructed, combined, and arranged in the manner and for the purpose set forth.

F. McMANUS.
